UNITED STATES PATENT OFFICE

132,682

DESIGN FOR A MOTORBOAT

George Forton, Detroit, Mich.

Application February 17, 1941, Serial No. 99,034

Term of patent 3½ years

To all whom it may concern:

Be it known that I, George Forton, a citizen of the United States residing at Detroit, in the county of Wayne and State of Michigan, have invented a new, original and ornamental Design for Motor Boats, of which the following is a specification, reference being had to the accompanying drawing, forming part thereof, wherein:

Fig. 1 is a plan view of a motor boat showing my new design.

Fig. 2 is a side elevational view of same.

Fig. 3 is an elevational view of the front end of the boat.

Fig. 4 is a rear elevational view of that portion of the boat to the right of the indicating line 4—4 of Fig. 2.

I claim:

The ornamental design for a motor boat, as shown.

GEORGE FORTON.
